UNITED STATES PATENT OFFICE.

BRUCE FORD, OF PHILADELPHIA, PENNSYLVANIA.

SECONDARY OR STORAGE BATTERY.

1,376,928.

Specification of Letters Patent.

Patented May 3, 1921.

Original application filed April 13, 1916, Serial No. 91,025. Divided and this application filed January 4, 1919. Serial No. 269,580.

To all whom it may concern:

Be it known that I, BRUCE FORD, a citizen of the United States, and a resident of Philadelphia, in the county of Philadelphia and 5 State of Pennsylvania, have invented certain new and useful Improvements in Secondary or Storage Batteries, of which the following is a specification.

This application is a division of my application serially numbered 91,025.

The principal object of the present invention is to improve secondary or storage batteries in regard to structure and operation in such a way that they can be successfully 10 operated by unskilled users and are capable of comparatively inexpensive and easy manufacture. Another object of the present invention is to provide a battery terminal which not only prevents any confusion in 15 connecting up a number of cells, but also provides a flexible inter-cell connection consisting of comparatively few parts.

The invention will be claimed at the end hereof, but will be first described in connection with the accompanying drawing, forming 20 part hereof, and in which—

Figure 1, is a side view of a portion of a cell provided with a battery terminal embodying features of the invention, and 25

Fig. 2, is a face view of one of the terminals.

In the drawings the terminal 1 is rigid, while the terminal 2 is of unlike polarity and is flexible and comparatively long. One 30 way of producing this relative rigidity and flexibility is by the use of appropriate materials, for example, lead alloyed with different proportions of antimony. Near the end of each terminal there is a bolt hole 3. Each 35 of the cells is equipped in the manner described and in this way any confusion in con-

necting up a number of cells is avoided and the cells may be connected by means of a single bolt, or the like, passed through the apertures 3 and this is a simple, expeditious 45 and safe method of connecting up the cells. Simple because the long terminals obviously must be connected to the short terminals and this insures the proper arrangement of polarity in the connection of the several cells, 50 expeditious because there is but a single bolt to be applied, and safe, because the connection between the cells is flexible and so mechanically durable and unlikely to be broken or detached.

I claim:

1. A storage battery cell provided with a plate structure having terminals of opposite sign and whereof one is relatively rigid and the other relatively flexible and of greater 60 length than the rigid terminal, said terminals serving to avoid confusion in connecting a number of cells and to provide flexible inter-cell connections of comparatively few parts.

2. In a storage battery the combination of a plurality of cells each having a rigid terminal and a relatively long and flexible terminal, and all the rigid terminals being of one polarity and all the flexible terminals 70 being of the other polarity, substantially as described.

3. In a storage battery the combination of a plurality of cells each having a rigid terminal and a relatively long and flexible 75 terminal, and all the rigid terminals being of one polarity and all the flexible terminals being of the other polarity, and means for connecting the extremities of the flexible terminal of one cell with the rigid terminal of 80 an adjoining cell, substantially as described.

BRUCE FORD.
